DESIGN FOR A TOY

Elmer C. Ruehle, Alhambra, Calif.

Application December 15, 1944, Serial No. 116,910

Term of patent 7 years

(Cl. D34—15)

To all whom it may concern:

Be it known that I, Elmer C. Ruehle, a citizen of the United States, residing at 1305 W. Hellman, Alhambra, in the county of Los Angeles and State of California, have invented a new, original, and ornamental Design for Toy, of which the following is a specification, reference being had to the accompanying drawing, forming part thereof.

Fig. 1 is a perspective view of the toy showing my new design; and

Fig. 2 is a top plan view of the toy, a portion of the handle being broken away for convenience in illustration.

I claim:

The ornamental design for a toy, as shown.

ELMER C. RUEHLE.
